UNITED STATES PATENT OFFICE.

EDWIN HANSALPAKAR, OF BROCKTON, MASSACHUSETTS, ASSIGNOR TO BROCKTON HEEL COMPANY, INC., OF BROCKTON, MASSACHUSETTS, A CORPORATION OF MASSACHUSETTS.

HEEL-BUILDING MACHINE.

Application filed August 21, 1920. Serial No. 405,131.

To all whom it may concern:

Be it known that I, EDWIN HANSALPAKAR, a citizen of the United States, residing at Brockton, in the county of Plymouth and State of Massachusetts, have invented new and useful Improvements in Heel-Building Machines, of which the following is a specification.

The subject with which the present invention is concerned is a heel-building machine, and particularly one adapted for use in connection with a chute into which the heels when built are pushed by a part of the machine. It will be noted, however, as the invention is explained, that many of its features are not dependent on the use or cooperation of a chute, wherefore my claim to protection for such features is general to a heel builder of any type having those features; and as to the same, the detailed description hereinafter given of a particular machine embodying my invention and combined with a chute is illustrative and without limiting significance.

The invention has for its objects the following. First, to combine with the presser head of a heel building machine a gage contrivance adapted to center and aline the lifts of the heel in process of building, before applying pressure thereto. It is a part of this object to adapt the gage contrivance to tapered heels of different heights and degrees of taper. Second, to control the operating cycle and stopping of the machine at the end of the cycle by the presser head. Third, in a chute machine, to provide for adjustment of the entrance of the chute conformably to heels of different dimensions, eliminating special molds. Fourth, to prevent the heels from backing to any extent out of the mouth of the chute. Fifth, to permit or cause movement of the presser head into and out of the line of pressure application, and to effect its movement in an exact path in that line, by simple means. Sixth, to build tapered heels in a chute with the aid of tapered separating blocks. Other objects relating to improved characteristics of structure and operation of the machine, appear from the following specification and appended statements of claim.

The exact nature and scope of the invention can best be stated in connection with a detailed description of a particular machine

containing in practical embodiment the 55 principles of the invention in the form which at the present time I consider superior to other possible forms. The particular machine here referred to is illustrated in the drawings furnished herewith, and therein:

Figure 1 is a side elevation of the machine.

Figure 2 is a front elevation.

Figure 3 is a plan view of the front part 65 of the machine, omitting the presser head and the driving mechanism.

Figure 4 is a plan view (on a larger scale) of the presser head.

Figure 5 is a horizontal cross section of 70 the heel chute and its adjusting means taken on line 5—5 of Figure 2.

Figures 6, 7, and 8 are detail views of 75 the presser head in front, side, and rear elevation, respectively.

Figure 9 is a cross section on line 9—9 of Figure 1.

Figures 10 and 11 are side and rear elevations of the presser head carrying slide, with its operating means shown in elevation.

Figure 12 is an elevation showing the means for guiding the pressure head in its pressing strokes.

Figure 13 is a perspective view of the dog which constitutes part of the means last referred to.

Figure 14 shows a plan view and a side view of one form of separating block used in building tapered heels.

Figure 15 is a side view of another form 90 of separating block.

Figure 16 is a side view of a tapered heel which may be built with this machine.

Figure 17 is a detail plan view showing the brake by which the machine is stopped 95 at the end of each operation or cycle.

Figure 18 is a view similar to a portion of Figure 2, showing certain features hereinafter described.

Figure 19 is a section on line 19—19 of 100 Figure 18.

The same reference characters designate the same parts wherever they are found in all the figures.

The heels *h* built in this machine are 105 blanks or blocks consisting of lifts piled upon one another and united by adhesive. They are built by an operator who assembles

a prescribed number of lifts in a prescribed order in a pile, after coating them with paste, or any other adhesive, and who, upon completion of the assemblage, moves a 5 presser head over it and then sets mechanism in operation which causes the head to bear against the assemblage and press the lifts firmly together. When the adhesive with which the lifts have been coated has 10 dried or set, the heel is ready to be compressed in a heel compressor and thereafter applied to a shoe, or to be applied to a shoe directly without being previously compressed. Having thus indicated the product 15 for the making of which this machine is designed, I will now proceed with a description in detail of the machine.

1 is a base or bed designed to be set on the floor of a factory, or on any other supporting foundation, and on which are mounted uprights 2, 3, and 4. The upright or frame 2 rises to a height convenient to the operator (who usually sits in front of the machine) and terminates in what may be called, 25 for the purposes of this description, a table 5, around which are arranged the usual bins or compartments (not shown) containing the constituent lifts of a heel. This table in the machine here being described, secures 30 and positions a chute, in the mouth of which heels are built. A filler block, later described more in detail, placed in the mouth of the chute and held there preferably by friction, provides the surface whereupon the 35 lifts are assembled, and at that time and for that purpose is virtually a part of the table. A breast gage 6, rising at the front of the chute, assists the operator in alining the lifts while building the heel.

40 The chute occupies at its upper end, a central space in the table and is composed of four longitudinal bars; the front bars 7 and 8, of angle formation, which embrace the breast corners of the heel, and the rear bars 45 9 and 10, with concave curved interior surfaces which bear against the rear part of the heel at each side. This construction is of advantage because, since the bars may be adjusted toward and away from one another, the chute may be fitted to heels of all 50 sizes and styles and caused to exert the desired frictional resistance to their progress. It has another advantage in that spaces are left between the bars which accommodate 55 the fingers or jaws of the presser head, later described. The rear bars 9 and 10 are hung from the table by angular straps 11 and 12, respectively, having vertical arms which are bolted, or otherwise suitably secured, to the 60 bars, and horizontal slotted arms which lie on the table and are secured by bolts 13 passing through their slots 14 and into the table. Retainer guide plates 15 secured beside and forward of the horizontal arms of these 65 straps limit their freedom of movement to a

straight crosswise line. Thus the rear bars are adjustable only laterally, or crosswise, and not to front and rear.

The front bars are adjustable both crosswise and to front and rear, and thereby the chute may be adjusted to heels of different widths and lengths, but the position of the rear point as to heels of all sizes remains approximately the same. A cross bar 16 occupies transverse notches 17 (shown dotted in Figure 3) in the front sides of the front bars 7 and 8, and is retained therein by blocks 18, bolted to the front bars and overlapping such cross bar, with enough freedom to permit lateral sliding movement of 70 the front bars. The ends of the cross bar rest in guideways 19 running from front to rear in the edges of the wings of the table which flank the central space previously mentioned, and are retained by the overlapping edges of the guide plates 15. Thus the front bars of the chute are also hung from the table. Adjustments of the front bars rearward and forward are made by sliding the cross bar 16 to front or rear in these 75 guideways, while set screws 20 threaded through lugs 21 at the front edge of the table hold the front bars against the heels of the size to which the chute is adjusted, with such pressure as is needed to make the 80 heels firm. The side bars (each front and rear bar at either side of the chute being a pair of "side bars" within the meaning of that term as now used) are likewise adjusted to the width of the heel and held against 85 spreading, by lateral adjusting screws 22, 23 threaded through webs 24 and 25 at the sides of the frame 2 beneath the table, which bear against longitudinal bars 26 and 27 confined 90 between the outer faces of the side bars and said adjusting screws (Figs. 3 and 9). Each of said longitudinal bars rests on a pin 28 projecting from the side of the adjacent front bar, and on the head of the bolt which secures the corresponding rear bar to its 95 supporting strap. The longitudinal bar is also notched in such a way as to provide a shoulder 29 to bear against the adjacent strap (Fig. 9) and prevent the bar from 100 working out of place.

The chute is further prevented from spreading, and adjusted to the size of heel being made, at a lower point, by means of a front set screw 30 and side set screws 31 held by a U-shaped strap or guard 32, which is made fast to the upright frame 2, and the screws bear against, respectively, a plate 33 in front of the chute, and side plates 34 at the sides of the chute. The rear bars are there braced by a rear cross pad 35 secured to the upright frame 2 (Fig. 2). A cross red 36 fixed in the guard 32 supports the forward ends of the side plates, and they in turn support the front plate.

The breast gage 6 is provided by two 130

- plates rising from the front bars of the chute, to which they are secured by splice plates 37 and screws, being removable to permit substitution of appropriate gages for 5 heels of different heights. A top gage 38, having a short projecting lip, is secured to the top of the breast gage and informs the operator when a heel has been built to the required height.
- 10 A presser head 40 is provided to align or centralize the lifts and apply pressure endwise to the heels, forcing them into the chute. To this end, the head is movable, both laterally from a position at the rear 15 of the chute to one directly over, and vertically in line with, the chute. It is carried by a swinging arm 41 pivoted by a pin 42 to a slide 43 which travels in a guideway 44 at the rear of the upright frame 2 and 20 parallel to the chute. The means connecting the head to this arm 41 is a lateral arm 45 secured to the upper end of the swinging arm, and a shank 46 on the head passing 25 slidingly through the lateral arm and limited as to its downward movement by a stop block 47 fitted adjustably on the shank and secured thereto by a set screw 48. A guide pin 49 rises from arm 45 through the stop block and prevents the head from rotating 30 in this arm. A handle 50 for the grasp of the operator enables the head to be swung forward over the assembled heel. It is normally drawn back to its retracted position (shown in Fig. 1) by a spring 51 connected 35 to the swinging arm 41 and anchored to an abutment rod 52 extending rearward from the slide 43. Fingers or jaws 52^a, 52^b, at the sides, and 53 at the rear, of the head depend therefrom and centralize the 40 lifts of the heel assemblage when the head is pulled forward. The side jaws then wipe along the sides of the heel and the rear jaw comes to bear on its rear edge, applying pressure laterally to the lifts in the most 45 efficient manner to shift them upon one another in case they should have been imperfectly located in the first place. The condition just suggested usually obtains in practice for the demands of rapid production 50 forbid the operator to take time for nicely placing the lifts; but the provision of the centralizing jaws makes it unnecessary for her to do so, since the jaws will take care of any such irregularities as occur in ordinarily skillful rapid heel building. These 55 jaws have inner edges suitably inclined or disposed to conform to the taper of the heel being built; and they are detachably secured to the head, in grooves 54 in the sides thereof by clamps 55, 56, and screws 57, to permit substitution of others adapted to any style of heels, whether straight or tapered more or less. The attaching means just described locate the jaws to come in 60 line with the spaces between the bars of the chute when the head is brought into its operative position, while the guide pin 49, cooperating with the stop block 47, prevents any such rotation of the head as would then cause disalignment of the jaws from such 65 spaces.
- 70 Adjustment of the shank 46 in the stop block 47 allows the head to be placed more or less below the arm 45 (which is always at approximately the same height in the normal position of rest, represented in these drawings) prior to the compression stroke, and thereby located in a path wherein the jaws, when the head is pulled forward, will bear on the edges of the particular heel, 75 whether high or low, being built. And different heads, suited to heels of various horizontal dimensions, may be substituted for one another upon the arm 45.
- 80 The lateral arm may also be adjusted across the swinging arm to bring the head into exact alignment with the chute, and for that purpose it has a tongue and groove sliding engagement, indicated by dotted lines at 511 in Figure 1, with the upper end 85 of the swinging arm, and is retained thereon by links 521 pivoted by a pin 531 to the swinging arm, and a clamp 541 passing over the reduced and threaded ends of such links 90 and retained thereon by nuts 551.
- 95 Power mechanism under the control of the operator gives the head its downward or compressing stroke. This mechanism consists of a belt pulley 561, loosely rotatable, and adapted to coact with a friction clutch member 571 on a shaft 58, which carries a pinion 59 meshing with a large gear 60 on a shaft 61. The latter shaft carries a pinion 62 meshing with the gear 63 on a shaft 64, which is rotatable independently 100 of shaft 58. On the shaft 64 is a crank arm 65 having a crank pin 66 (Figs. 10 and 11) which occupies a block 67 arranged to slide in a transverse guideway in the rear side of the slide 43 which carries the swinging arm whereon the presser head is mounted. The shafts 58, 61, and 64 are arranged in suitable bearings 69 and 70 on the uprights 3 and 4 which rise from the base 1. This mechanism gives a continuous speed 105 reduction and power multiplication from the source of power to the point of delivery upon the head-carrying slide.
- 110 After the head has been brought into alignment with the chute it is retained there during the pressing stroke, by a dog 71 pivoted by a pin 72 between two brackets 73 which extends rearwardly from the upright frame 2 on both sides of the swinging arm 41. A spring 74 (Fig. 12) acts on the dog, pressing its free end toward the arm 41, and serving to turn the dog until its end face abuts against a wear plate 75 on the arm when the latter is drawn forward, as 115 shown in Fig. 12. Lips formed by a plate 120
- 125 130

76 secured to the dog crosswise then rest on the brackets 73, arresting movement of the dog. The length of the latter is such that when in the position last described it 5 holds the carrier arm 41 vertical, or in other words, in alinement with the path in which it travels during the compression stroke of the head. A feature of the dog is that, being unrestrained except by the light 10 spring 74 from upward movement, the friction of the wear plate against its end when the presser carrier rises, is enough to swing it back into its inoperative position, where it permits backward displacement of the 15 carrier arm 41. Its movement in this direction likewise is limited by the wings 76. Furthermore, if the operator in swinging the presser head forward, should release the latter before having brought it to the extreme 20 limit of forward movement, but yet far enough to let the forward end of the dog drop enough to secure the head against backward swinging, then the friction of the wear plate on the dog in the downward 25 stroke becomes effective to place the dog fully in its operative position.

For clutching the drive pulley 561 to the transmission mechanism through the clutch member 571, there is provided a treadle 78 30 convenient to the operator's foot on the end of a treadle arm or lever 79, pivoted at 80 to an upright 81 on the bottom plate. This lever has a short arm 82 carrying an adjustable stud 83 arranged to press on the hub 85 of the pulley and shift the latter endwise so that the clutch face with which it is 35 provided, complementary to the face of the clutch member 571, is crowded against the latter. When depressed, the treadle arm is held 40 in that position until released by the arrival of the carrier at the end of its upward travel. It is so held by a latch 84 on one arm of a lever 85, the other arm of which has a cam or wiper element 86 co- 45 operating with a pin 87 projecting from a bracket 88 on the slide 43. A spring 89 holds the lever with its wiper element against the pin 87 and tending to carry its latch element toward the treadle arm, and 50 over said arm when the latter is depressed. When the carrier slide descends after depression of the treadle, the descent of pin 87 past the inclined cam surface 86 allows lever 85 to be moved in this manner and to catch 55 the treadle in its depressed position. When the carrier rises, the pin 87 by wiping along the cam surface 86 moves the latch lever 85 in the reverse direction and allows the treadle arm to be raised by a spring 90. 60 This occurs when the presser carrier is near the top of its travel, and then a brake 91 is applied to the disk which carries the clutch element 571. This brake is carried by a lever 92 pivoted to a bracket 93 on the up- 65 right 4 and pressed by a spring 94 toward

the adjacent face of the disk. The treadle arm carries a wedge 95 which, when the treadle is depressed, crowds the lever 92 away from the disk and releases the brake, and when withdrawn by rise of the treadle 79 arm, allows the brake to be applied by spring 94. Hence the operator need give no further attention to the power operation of the machine than to depress the treadle, and immediately after the head has started 75 on its downward course, to leave the treadle free. Thereafter the head carrier itself causes disconnection of the driving clutch and setting of the brake at the limit of its upward travel, through the means thus described. 80

A retainer is provided to hold the heels in the chute after they have once been placed therein. Said retainer is a hook-like finger 85 96 on the upper end of the arm 97 which is pivoted by a pin 98 to a bracket 99 attached to the front bars of the chute. The attaching means comprises a slotted base plate 100 on the bracket, through the slots of which clamping bolts 101 pass into said front bars. 90 The hook or finger 96 slightly overlaps the breast edge of a heel inserted in the chute. It is yieldingly held in that position by springs 102, and its upper side adjacent to the end is beveled so that the pressure of a descending heel will push it forward out of the way. 95

The filter blocks previously referred to 100 perform an important function in the operation and effect of the machine, and constitute important parts of the machine combination. One construction of such block, designated 103, is shown in Figure 14, and another construction of the block designated 104 is shown in Figure 15. The blocks are 105 of wood, or other sufficiently firm, strong, and durable material, preferably impregnated or coated with a substance, such as paraffin, which makes them repellent to the adhesive with which the heel lifts are coated, so that they will readily separate from the heels upon emergence from the chute. In 110 outline they conform approximately to the largest lift of the heel, and those provided for use in building tapered heels are wedge-shaped to bring the upper face of the tapered heel horizontal, for such heels necessarily have their opposite end faces disposed at an angle to one another. The chute is 115 adjusted to fit the spacing blocks and to apply pressure to the corners and each side thereof. Thus frictional resistance is exerted against the passage of the blocks through the chute, and this resistance must be overcome by pressure applied by the head 120 40 through the heel. This pressure compresses the lifts of the heel together; and it is maintained and augmented by successive filler blocks and heels built on top of one another and successively forced into the 125 130

chute. When the chute contains a long series of heels and blocks, the cumulative frictional resistance of all the blocks must be overcome in putting each new heel into the chute, and the overcoming of this resistance necessitates applying relatively great pressure to the new heel. Thus, the heels as soon as assembled, are put and maintained under pressure; and as the chute is intentionally made long enough with respect to the time required for drying or setting of the adhesive to enable such adhesive to dry or set before the heel emerges from the lower end of the chute, it follows that the heels are held strongly compressed until they have dried. The retainer 96 contributes to this end by preventing relaxation of the pressure upon the heel last assembled after it has been forced into the chute, and before the next new heel has been pressed against it. Hence there is no intermission of the pressure and no opportunity for the bond of the adhesive to be broken or weakened at any stage in the course of drying.

25 The difference between the two types of filler blocks shown in the drawings consists in that the block 103 has a longitudinal rib 105 on its upper surface designed to limit the area of contact with the adjacent lift 30 of the heel, while the block 104 has no such rib. Each block has a notch 106 in its breast end designed to receive the retainer hook 96, so that it may rest squarely against the last heel placed in the chute, 35 without causing or requiring displacement of the retainer.

The machine and its chute are made for use in the vertical position, and the table is arranged horizontally because this is the 40 most convenient arrangement on all accounts, as well for the operation of building heels as because it enables a chute of sufficient length to be provided by extending it through the floor on which the machine is installed to a lower floor or the basement of the factory. But nothing in the way of limitation of the scope in which I claim protection is to be implied therefrom, since the principles of the invention may be 45 embodied in machines otherwise arranged and operated, as for example, in a horizontal position or at an inclination.

It is to be observed that certain features of the invention, particularly those residing 50 in the presser head, its mode of action, its carrier, and the operating means therefor, are not necessarily limited to the combination and use with a chute machine, but are applicable to machines having fixed tables 55 as well.

The mode of operation of the machine has been sufficiently understood from the foregoing description to make unnecessary any special statement of operation. It is sufficient to say that the operator's part con-

sists in assembling the lifts of a heel upon the filler block placed over the last built heel, in then pulling the presser head forward over the complete assemblage of lifts, thereby causing the jaws 52^a and 53 to align or centralize the lifts with one another, and in finally depressing and releasing the treadle. Thereafter the mechanism automatically lowers the presser head, forcing the new heel into the chute and propelling the whole series in the chute one stage forward, and then raises the head and stops with the head in its raised and retracted position shown in the drawings.

80 Figures 18 and 19 show an alternative construction of the top gage 38, shown by Figures 1 and 2. The top gage, instead of being composed of a single piece attached to the plates 6, forming the breast gage, and having no vertical adjustability, is composed of two pieces 38^a, movably secured to said plates and adjustable vertically to conform to heels of different heights, the plates 6 having vertical slots 6^a, and the top gage pieces being secured to the plates 6 by clamping screws 38^b passing through said slots.

85 Figures 18 and 19 also show oppositely inclined side gages 38^c adapted to bear on opposite sides of a heel *h*, the breast and top of which bear respectively on the breast gage and the top gage. The side gages are adjustably secured by screws 38^d, passing through slots 38^e in the base portions of the side gages, so that said gages are adjustable toward and from each other.

90 The chute bars may be so adjusted or spaced, that the filler blocks are loosely movable in the chute, so that there is no frictional resistance to their movement in the chute.

95 What I claim and desire to secure by Letters Patent is:

1. In a heel building machine, a support, a presser adapted to be moved both transversely of a previously assembled heel blank on said support and longitudinally of such heel blank so placed, and having jaws for centrally placing the lifts.

110 2. A heel building machine comprising a support on which heel lifts may be assembled, a presser head mounted with provision for movement laterally over and away from the heel location, members carried by said head adapted to bear on the edges of the assembled heel to centralize the lifts thereof when the head is moved over the building location, and means for forcing the head toward said support for compressing the assembled heel.

115 3. In a heel building machine a vertically reciprocatable head carrier and a presser head mounted on said carrier with provision for movement transversely to the direction in which the carrier is reciprocated, said

head having lift-centralizing jaws adapted to bear on the edges of a previously assembled heel.

4. In a heel building machine, supporting means for the heel being built, a slide mounted below said supporting means, a swinging arm pivoted to said slide, and a presser head carried by the upper end of said arm with provision for movement laterally over said supporting means and away therefrom, the slide being movable in a line transverse to the said lateral movement of the head, whereby to cause pressure-application by the head upon an assembled heel, and the head having lift-centralizing jaws.

5. In a heel building machine a carrier mounted to reciprocate in a given path, an arm forming part of said carrier pivoted to and rising from the reciprocatable member thereof and adapted to swing laterally with respect to said path of reciprocation, and a presser head having lift-centralizing jaws secured to said arm and adapted to be shifted in position by the swinging movement thereof.

6. A heel building machine comprising a support on which heels may be built, a slide guided to move in a path approximately perpendicular to the plane of said support, an arm pivoted to said slide on an axis approximately parallel to the support, a transverse arm projecting from said swinging arm and adapted to be moved with the latter over and aside from the heel location, a presser having lift-centralizing jaws projecting toward the heel support from said lateral transverse arm, and mechanism for moving said slide to force said presser against a heel when the latter has been shifted thereover.

7. A heel building machine comprising a support on which heels may be built, a slide guided in a path approximately perpendicular to the plane of said support, an arm pivoted to said slide on an axis approximately parallel to the support, a transverse arm projecting from the swinging arm and adapted to be moved with the latter over and aside from the heel location, a dog pivoted back of the swinging arm adapted to be displaced into a position between its pivot and the arm when the latter has been shifted to bring the presser over the heel location whereby to prevent retraction thereof during the pressing action, a presser projecting toward the heel support from said lateral transverse arm, and mechanism for moving said slide to force said presser against a heel when the latter has been shifted thereover.

8. A heel building machine as set forth in claim 7 in which said dog is arranged to be displaced from the position described by frictional engagement with the swinging arm to permit withdrawal of the presser

from over the heel location, upon return of the slide and presser from the heel pressing operation.

9. In a heel building machine a sliding carrier guided to move in a given path, an arm pivoted to said carrier arranged to be shifted into and out of alignment with said path, a presser carried by said arm and a dog pivoted at one side of the arm and yieldingly held with its swinging end abutting against the arm, and in a position causing it to slip into the space between its pivot and said arm when the latter is in alignment with the path of movement of the slide, said dog being further so arranged that its engagement with the arm causes it to be swung out of such space when the arm is returned after making a pressing stroke.

10. In a heel building machine a sliding carrier guided to move in a given path, an arm pivoted to said carrier arranged to be shifted into and out of alignment with said path, a presser carried by said arm, and a dog pivoted at one side of the arm arranged to be placed with its swinging end abutting against the arm when the latter is in alignment with the path of movement of the slide, and to be swung out of the way permitting the arm to shift out of such alignment, the free end of the dog being arranged to engage the swinging arm, whereby the friction of the latter is enabled to swing the dog out of restraining position upon reciprocative movement of the slide and arm in one direction, and to complete the displacement of the dog into said position upon the reciprocative movement in the opposite direction.

11. In a heel building machine, a heel presser, a back and forth moving carrier for said presser, power mechanism for removing said carrier including a clutch, an operator-controlled means for connecting said clutch, a latch for holding said means in the clutch-connecting condition, and means by which said carrier causes disengagement of said latch at the end of each cycle to permit disconnection of said clutch.

12. In a heel building machine, a heel presser, a back and forth moving carrier for said presser, power mechanism for moving said carrier including a clutch, and a brake adapted to stop movement of said mechanism, an operator-controlled means for connecting said clutch and releasing said brake, a latch arranged and adapted to retain said means in a position where it effects the last-mentioned results, and means by which said carrier in its movement displaces said latch.

13. In a heel building machine a presser carrier, a control lever, a latch arranged and adapted to hold said control lever in a certain position, an arm having a cam element controlling the condition of said latch, and

a member carried by said carrier co-acting with said cam to cause release of the latch at a selected time in the travel of the carrier.

14. In a heel building machine a presser for acting upon lifts assembled to form a heel, power mechanism for driving said presser, an operator controlled lever for putting said power mechanism into action, a latch arranged to hold said lever in the position which it occupies when said mechanism is in action, and means normally arranged to be operated by the movement of said presser on its return from each pressing stroke for releasing said latch and permitting the power mechanism to become inactive.

15. In a heel building machine, a reciprocatable heel presser, power mechanism including a disconnectible clutch for driving said presser back and forth, a treadle adapted to be pressed upon by the operator for setting said clutch, a latch spring-actuated to retain the treadle in the position where in it is then placed by the operator, a cam device associated with said latch, and a tripper movable with the presser and arranged to act upon said cam device during the return stroke of the presser so as to displace said latch and permit release of the treadle.

16. In a heel building machine, a frame, a presser, a chute consisting of substantially parallel bars, the ends of said bars constituting the mouth of the chute and being adjustable to vary both dimensions of such mouth, and means for holding said chute in connection with said frame and with its mouth in position to receive heels while still engaged with said presser.

17. In a heel building machine a supporting frame, and a chute consisting of two front bars and two rear bars, the rear bars being adjustable laterally toward and away from one another, but prevented from displacement in the front and rear directions, and the front bars being similarly adjust-

able, and also adjustable toward and away from the rear bars.

18. In a heel building machine, a frame, a chute consisting of separate longitudinal bars, the upper ends of which bars form the mouth of the chute, means on the frame for adjusting said bars at one end to determine the dimension and proportion of said mouth, and adjusting means at a distance from such mouth arranged to bear on the said bars for holding them at a greater or less distance from one another.

19. In a heel building machine, a chute consisting of two front angle bars and two rear bars, a frame, angle straps connected to the rear bars and supported on said frame, with provision for adjustment of the rear bars toward and away from one another, a crossbar to which the front bars are connected with provision for movement toward and away from one another, said crossbar being supported on the frame movably toward and away from the rear bars, abutment screws arranged to bear on said crossbar to maintain the adjustments thereof, longitudinal bars crossing the front and rear bars at each side of the chute, and adjusting screws bearing on said longitudinal bars to maintain the lateral distance between the bars of the chute.

20. In a heel building machine, a chute consisting of separate longitudinal bars, means for adjusting said bars at one end to determine the dimension and proportion of the chute's mouth, and adjusting means at a distance from such mouth arranged to bear on the said bars for holding them at a greater or less distance from one another, the last-named adjusting means comprising a rigid frame work surrounding the chute, and adjusting screws held by said frame work and arranged to exert pressure from without against the chute bars.

In testimony whereof I have affixed my signature.

EDWIN HANSALPAKAR.
